UNITED STATES PATENT OFFICE.

JOHN BABIS, OF PHILADELPHIA, PENNSYLVANIA, ASSIGNOR, BY MESNE ASSIGNMENTS, TO S. S. WENZELL MACHINE COMPANY, OF PHILADELPHIA, PENNSYLVANIA, AND CHARLESTON, WEST VIRGINIA, A CORPORATION OF WEST VIRGINIA.

BOTTLE-WASHER.

SPECIFICATION forming part of Letters Patent No. 684,665, dated October 15, 1901.

Application filed April 24, 1899, Serial No. 714,238. (No model.)

To all whom it may concern:

Be it known that I, JOHN BABIS, a citizen of the United States, residing in Philadelphia, Pennsylvania, have invented certain Improvements in Bottle-Washers, of which the following is a specification.

One object of my invention is to so construct a cleaner for bottle-washing machines that the centrifugal force due to the rapid rotation of the cleaner can freely act to press the cleaner forcibly against the walls of the bottle, a further object being to provide a special form of "brush" designed to act effectively upon all portions of the interior of the bottle. These objects I attain in the manner hereinafter set forth, reference being had to the accompanying drawings, in which—

Figure 1 is a side view, partly in section, showing the cleaner as it appears when not in use. Fig. 2 is a view showing the cleaner acting upon the expanded portion or shoulder of the bottle. Fig. 3 is a view showing the cleaner acting upon the bottom of the bottle. Fig. 4 is an enlarged section on the line *v v*, Fig. 1. Fig. 5 is an enlarged section on the line *w w*, Fig. 1; and Fig. 6 is an enlarged section on the line *x x*, Fig. 1.

The rotating stem or spindle of the machine which carries the cleaner is shown at 1 in Figs. 1, 2, and 3, this stem being slotted at the upper end for the reception of the lower ends of two arms 2, which lie side by side in the slotted portion of the stem or spindle 1 and are pivoted thereto by a transverse pin 3, so that each arm is free to swing outwardly under the influence of centrifugal force when the stem 1 is rapidly rotated.

Each of the arms 2 consists of a flat blade of metal bent or twisted to the extent of a quarter-turn, so that the outer portion of each arm is at right angles to its inner portion and the outer portion of each arm carries a rubber brush of the character shown in Figs. 1, 4, 5, and 6. The said brush is made of rubber or equivalent material and consists of a socket 4, adapted for the reception of the outer end of the arm 2, to which it snugly fits, said socket having upon its outer side a thin central projecting fin 5. At its upper end the socket 4 joins an upwardly-

projecting finger 6 and an outwardly-projecting finger 7, and along both of said fingers extends a central projecting rib 8.

As the fin 5 and fingers 6 and 7 are preferably flexible they permit of the contraction of the cleaner, so that it can be readily introduced into or drawn from the neck of a bottle; but when the stem or spindle 1 is rotated the centrifugal action tends to throw the brushes out against the inner wall of the bottle with a force dependent upon the speed of rotation of said stem or spindle, the fin 5, fingers 6 and 7, and rib 8 brushing against the walls of the bottle and accommodating themselves to any and all of the contours of the latter. Thus, as shown in Fig. 2, the parts will readily accommodate themselves to the curved shoulder of the bottle, while, as shown in Fig. 3, the fingers 6, which as the stem 1 rises in the bottle were first projected into the narrow space between the sides of the bottle and the raised central bulb at the bottom of the same, will, as the movement is continued, follow the contour of said central projection or bulb, the fingers 7 entering the contracted annular space between said bulb and the sides of the bottle, thus effectually reaching and cleansing the portion of the bottle which is usually most difficult of access.

In some cases the spindle 1 may have but a single swinging arm; but it is preferable in all cases to have two or more arms equidistantly disposed, so as to insure proper balance.

Having thus described my invention, I claim and desire to secure by Letters Patent—

1. The combination in a bottle-cleaner, of a rotatable stem or spindle, with an arm or arms pivoted thereto so as to be free to swing outward by centrifugal action and each carrying a cleaning-brush independent of and disconnected from that of the other arm, substantially as specified.

2. The combination of a rotatable stem or spindle, with a cleaner-arm pivoted thereto so as to be free to swing outwardly, said arm consisting of a flat blade or plate bent or twisted to the extent of a quarter-turn so that its outer portion is at a right angle to the in-

- ner or pivotal portion, said outer portion carrying a brush or cleaner and the inner portion being pivoted to the spindle, substantially as specified.
- 5 3. The within-described brush for a bottle-washing machine, said brush being composed of rubber or other flexible material and having a socket adapted for the reception of a carrier-arm, and at the outer end of said 10 socket, flexible fingers projecting therefrom at different angles, and both free at their outer ends, said fingers being adapted to simultaneously act upon adjacent portions of the walls of the bottle, substantially as specified.
- 15 4. The within-described brush for a bottle-washing machine, said brush consisting of a socket adapted for the reception of a carrier-arm and having at the end flexible fingers projecting therefrom at different angles, both of 20 said fingers having on their outer faces projecting ribs and both being free at their other ends, substantially as specified.
5. The within-described brush for a bottle-washing machine, said brush consisting of a 25 socket adapted for the reception of a carrier-
- arm and having a central flexible fin projecting outwardly therefrom, substantially as specified.
6. The within-described brush or cleaner for a bottle-washing machine, the same consisting of a socket adapted for the reception of a carrier-arm and having a central flexible fin projecting outwardly therefrom, and at the end a flexible finger projecting therefrom at an angle, substantially as specified. 30
7. The within-described brush for a bottle-washing machine, the same consisting of a socket adapted for the reception of a carrier-arm and having a central flexible fin projecting outwardly therefrom, and at the end flexible fingers projecting from the socket at different angles, substantially as specified. 35
- In testimony whereof I have signed my name to this specification in the presence of two subscribing witnesses.

JOHN BABIS.
